DOBBY FINGER FOR LOOMS

Application filed December 19, 1930. Serial No. 503,539.

This invention relates to improvements in dobbies fingers for looms and it is the general object of the invention to facilitate the manufacture of pressed steel fingers to the end that they may be more efficiently and accurately assembled.

Loom dobbies usually operate with a plurality of so-called fingers which are acted upon directly by the pattern mechanism, such for instance, as a chain provided with pegs. The fingers have their under sides grooved so as to maintain engagement with the pegs as the latter move under them and it is an important object of my present invention to provide a finger the major part of which is made of relatively soft sheet steel but the peg engaging-run of which is made of relatively hard steel. In previous constructions of this kind the hardened steel part has been located between the folded sides of the finger body and this construction has required the run to be held in position while the bending of the outer inclosing sheath was being completed. It is another object of my present invention to make the finger so that the hardened run can be applied to one side of the finger after the folding of the finger body has been completed.

In previous constructions the groove of the run has been made by folding together opposite edges of a relatively thin piece of hardened steel so that the peg has not had contact across the whole of its upper end with metal, thereby causing uneven wear. It is another object of my present invention to provide a run which will have a continuous surface to engage the peg, thus insuring uniformity of wear.

With these and other objects in view which will appear as the description proceeds, my invention resides in the combination and arrangement of parts hereinafter described and set forth in the claims.

In the accompanying drawings, wherein a

convenient embodiment of my invention is set forth,

Fig. 1 is a front elevation of a dobbie equipped with fingers made according to my present invention,

Fig. 2 is a fragmentary top plan view taken from the direction of arrow 2, Fig. 1, and on an enlarged scale,

Fig. 3 is a front elevation of a dobbie finger made according to my present invention,

Fig. 4 is a top plan view of the finger shown in Fig. 3,

Figs. 5 and 6 are enlarged vertical sections on lines 5—5 and 6—6, respectively, of Fig. 3,

Fig. 7 is a plan of the blank which forms the outer folded and inclosing part of the finger,

Fig. 8 is a plan of the filler located between the folded sides of the inclosing sheath, and

Fig. 9 is a perspective view of the run.

Referring to Fig. 1, I have shown a dobbie jack 20 movable about a fixed pivot 21 and having a back lever 22 pivoted thereto as at 23. The upper and lower ends of the lever have pivoted thereto hooks 24 and 25, respectively, which are adapted for co-action with oppositely reciprocating knives 26. The lower hooks are adapted for the upturned tail 27 of one form of figure, whereas the upper hooks are controlled by rods 28 the lower end of which have engagement with a straight tail 29 formed as part of another type of finger. A pattern mechanism designated generally at 30 is provided with finger lifting pegs 31 of the usual form, and a comb 32 having guide pins 33 for the fingers may also be employed. The sequence of pegs 31 under the several fingers determines the order in which the harness jacks 20 shall be moved and thus control the shedding of the loom.

The matter thus far described is of common construction and forms no part of my present invention.

Although I have described two forms of

fingers which are rendered necessary by the fact that the hooks are controlled in different ways, yet the essential features of my invention are the same for both of these fingers and

5 I will therefore describe the invention with relation to but one of them, namely, that which controls the lifter rod 28.

Referring to Fig. 3, it will be seen that I have provided a central filler 40 having a 10 weighted wing 41 to lie between the pins 33. In the instance illustrated the filler has an inwardly extending tail 42 shown at the left at Fig. 8 and also has a downwardly opening slot 43 to receive a fixed supporting shaft 44 around which the fingers move as a pivot. The filler forms the central part of the finger and the wing 41 is preferably sufficiently heavy to assist the other parts of the finger in overbalancing the weight of the rod 28 15 and the associated hook 24. The lower edge of the filler lying between the slot 43 and the wing 41 may be arcuate, as at 45.

Surrounding a portion of the filler is an 20 inclosing sheath member 50 which, as shown in Fig. 5, is generally U-shaped in vertical cross section. The sheath is provided with open slots 51 designed to register with the slot 43. Extending inwardly from the slots are two arms 52 substantially the same as the 25 corresponding part 42 of the filler. The sheath may have an arcuate edge 53 on one side similar to edge 45 of the filler, while the other side is cut out to form a large notch 54, Fig. 7. A short slot 55 shown at the right hand end of Fig. 7 is provided to receive a 30 part of the wing 41.

The run R which engages the pegs is 35 shown particularly in Fig. 9 and comprises an upright wall 60 from the lower edge of which extends an arcuate, bent edge 61 the lower surface of which is concave in a direction transversely of the finger for the purpose of receiving the pegs 31. The arcuate curvature of the bend 61 corresponds to the 40 edges 45 and 53 of the filler and sheath, respectively.

In assembling the finger, the filler 40 is 45 placed within the previously folded sheath so that it assumes the position shown in Fig. 5, the slots 51 registering with the slot 43 and the arms 42 and 52 also being in register. These parts may then be welded together, as at W. The run R is then positioned as indicated in Figs. 3 and 5 in notch 54 with the 50 lower arcuate run 61 extending under the filler and projecting over to the arcuate edge 53. The run is provided with opposite vertical edges 62 which engage edges 63 on the sheath while the upper edge 64 of the run engages the top edge 65 of the notch 54, illustrated in Fig. 7. The run is then welded in 55 position to the filler and sheath, as indicated at X in Fig. 3, the outer surface 66 of the vertical wall 60 of the run being flush with the corresponding surface 67 of the sheath.

In this way that side of the finger which has the run applied thereto is smooth and will move without interfering with the adjacent finger.

From the foregoing it will be seen that I 70 have provided a form of pressed metal dobby finger wherein the sheath may be bent to final form prior to assembly and that the run for the pegs 31 is inserted in a notch defined in one of the vertical walls of the 75 sheath. In this way the run can be easily assembled without the necessity of a bending operation on the part of the sheath after the run is in position. It will also be seen that by means of a construction set forth herein 80 the groove in the lower side of the bend 61 is continuous from one side to the other of the finger so as to provide contact with the top of the pegs 31 such as will result in uniform 85 wear of the latter.

Having thus described my invention it will be seen that changes and modifications may be made therein by those skilled in the art without departing from the spirit and scope of the invention and I do not wish to 90 be limited to the details herein disclosed, but what I claim is:

1. In a dobby finger, an inclosing sheath of U-shaped cross section, one of the sides of the U having an opening therein, and a peg run set into the opening and secured with respect to the sheath. 95

2. In a dobby finger, an outer inclosing sheath formed generally of U-shaped cross section, a filler located between the sides of the sheath, one of the sides of the latter having an opening therein, and a peg run inserted in the opening and having a peg groove and held rigidly with respect to the sheath, and the filler. 100

3. In a dobby finger, a peg run element having the lower edge thereof bent to form a groove of continuous arcuate form from one side to the other thereof so as to present a continuous wearing surface to the peg of the dobby chain, and a dobby finger body to 110 which the sun is secured.

4. In a dobby finger, means defining a body for the finger, and a separate peg run element extending from one side of the body across to the other side and having a peg receiving groove formed therein. 115

5. In a dobby finger, means defining a body for the finger, and a separate peg run element extending from one side of the body across to the other side and having a peg receiving groove formed therein which is continuous from one side to the other of the finger to present uniform wearing surface to the peg of a dobby chain. 120

6. In a dobby finger, means defining a body for the finger, and a separate peg run element extending from one side of the body across to the other side and having a peg receiving groove formed therein, the run ele- 125

ment having a vertical portion, from the lower end of which extends a grooved arcuate peg-engaging section.

7. In a dobby finger built up of sheet metal elements, a peg run formed as one of said elements and having a concave peg receiving groove which is continuous in arcuate form from one side of the finger to the other side thereof.

10 In testimony whereof I have hereunto affixed my signature.

ALBERT A. GORDON.
